CARBURETING APPARATUS.

1,108,081.

Specification of Letters Patent.

Patented Aug. 18, 1914.

Application filed November 12, 1913. Serial No. 800,519.

To all whom it may concern:

Be it known that I, FRED S. OLIVER, a citizen of the Dominion of Canada, residing in the city and county of San Francisco and State of California, have invented new and useful Improvements in Carbureting Apparatus, of which the following is a specification.

This invention relates to air carbureting apparatus, and particularly pertains to an apparatus for use with hydrocarbons.

It is an object of the present invention to provide an automatically operating and novel apparatus for use with liquid hydrocarbons, such as gasoline.

It is a particular of the present invention to provide in such an apparatus a gasometer for receiving and holding the carbureted air under suitable pressure, and to provide a carbureting chamber and means for supplying a constant supply of volatile liquid thereto, with means for automatically maintaining a charge of predetermined level of the liquid.

A further object of the invention is to provide an air pump for discharging a current of air into the carburetor and means for operating the pump and connections between said means and the gasometer for automatically controlling the operation of the air pump and automatically interrupting or opening the liquid controlling means; and a further object is to provide an automatically operating device to maintain the liquid in a feed chamber at a predetermined level.

An important object of the present invention is to provide an air carbureting apparatus including a source of volatile liquid wherein may be contained a relatively small quantity of fuel to reduce the danger of explosion, and also to insure a constant renewal of the volume of volatile liquid, so that the natural segregation of the contents of the liquid into different grades will be avoided, so that the stream of liquid as fed to the carbureting chamber will be of substantially uniform gravity or richness, thereby avoiding fluctuations in the richness of the gaseous mixture produced by the apparatus.

The invention consists in the combination of a gasometer and a carburetor, with means for supplying a substantially constant charge of volatile liquid of uniform richness to the generating chamber, and means for

automatically controlling the period of operation of the generator to avoid excess carburetion; and further consists of a suitably driven blower or air feeding device automatically controlled during the operation of the apparatus, and further consists of a liquid pressure controlling mechanism for substantially balancing the pressures in a source of supply and a discharge head therefor.

The invention further consists of the parts and the construction and combination of parts as hereinafter more fully described and claimed, having reference to the accompanying drawings, in which—

Figure 1 is a general diagrammatic view of the apparatus with parts in sectional detail. Fig. 2 is a detail of the float operated liquid feed control valve. Fig. 3 is a detail sectional view of the automatic cut-off and feed regulator valve.

In its illustrated embodiment the invention includes a gasometer tank 2, mounted in a water seal 3, and having a discharge pipe 4 and an inlet or feed pipe 5 with a check valve 6 to prevent the return of the carbureted air therethrough, the gasometer 2 being provided with removable and variable weights 7 for the determination of the pressure of the mixture discharged from the gasometer.

The pipe 5 is connected at its upper end with a collecting chamber 10 discharging into the pipe, and provided with a cowl 11, the lower horizontal flange of which is disposed close to the plane of the normal level of a volatile liquid therein, any excess of which above the normal level for any cause, such as failure of the float to operate, will be returned by an overflow pipe 12 to a basin 13, which may be mounted in the ground or at some suitable location with relation to the apparatus, and which basin 13 is in communication with the collecting chamber 10 through means of a pipe 14 joined to the lower end of a carbureting chamber 15.

The carbureting chamber may be of suitable height and diameter, and is provided with a multiplicity of vertically superposed conical drain shelves 16, with central apertures at their bottom edges through which extends upwardly a supply or feed pipe 17 upon which is securely mounted conical deflectors 18 of somewhat less diameter than the diameter of the chamber 15, so that a

space is formed between the perimeter of the deflectors 18 and the adjacent walls of the chamber.

The feed pipe 17 is provided with a multiplicity of apertures 19 which preferably decrease gradually in size from the top down along the feed pipe. The upper end of the feed pipe is connected to a regulator valve 20, which may be set as desired to feed a suitable quantity of liquid from a feed chamber 21 to which the valve 20 is connected with a joint-forming valve seat 22 near the bottom of the feed chamber 21, which is here shown as connected to one side of the collecting chamber 10 and in free liquid communication therewith. The valve seat 22 receives with a spindle valve 23 which is suitably mounted in the chamber 10 and has an upwardly projecting stem upon which is mounted a collar 24 bearing a spring 26 acting against a loose collar 27, above which is disposed a lever 28 operable by a means hereinafter to be described, to open and close the outlet at the valve seat 22 above the regulator valve 20. Gasolene passes from chamber 21, through ports 22' formed in a tube 22" which acts as a guide for the stem of valve 23.

To the end of maintaining the desired quantity of oil in the head tank 21 at a given level and at the same time not cause its overflow to the oil pipe 12 of the chamber 10, there is mounted in the head chamber 21 a float 30 connected to a lever 31 of a valve 32 opening outwardly from the tank 21 and closing upon a seat 33 when the float 30 rises, and thus shutting off incoming oil from a supply pipe 34 which is connected to a source of supply or drum 35; it being understood that the drum 35 while here shown as arranged underground or in a safe position with relation to the apparatus, may be arranged overhead and at a suitable disposition so long as sufficient pressure can be obtained to feed the liquid as rapidly as desired to the carbureter. The top of the chamber 10 may have a partition as shown between float 30 and cowl 11.

Since the present arrangement shows the source of supply or drum 35 as underground or below the level of the head tank 21, suitable means are shown as an air pipe 36 by which air under pressure is conveyed to the drum from a compressor 37 of suitable type which may derive power from the motor 38 of any suitable character. The motor 38 is also utilized to drive a suitable air feed mechanism here shown as a blower 39 having a relief valve 40 automatically operable to open when a normal or desired pressure is exceeded. The blower 39 has a discharge tube 41 which discharges air into the lower end of the carbureter chamber 15, the air rising in circuitous paths upwardly through the drum as it passes the several superposed

and oppositely inclined deflectors and bafflers 16-18, down each of which the thin films of volatile oil will flow as discharging from the feed apertures 19 in the nozzle of the supply pipe 16, the rising column of air vaporizing the volatile liquid and passing into the chamber 10 as it issues from the open upper end of the carbureting chamber 15 and rises past the downwardly turned cowl 11 which tends to throw down the heavier contents of moisture in the rising column of air which has been enriched by the liquid, and passes thence from the chamber 10 through the pipe 5 into the gasometer 2.

The automatic charging of the gasometer 2 in proportion to the volume of carbureted air discharged therefrom is accomplished by means controlled by the rise and fall of the gasometer 2, which means operate to cut out the motor 38, thus stopping the operation of the blower 39 which forces air through the carbureting chamber 15, and also stopping the compressor 37 which generates pressure in the reservoir drum 35 to lift the oil to the head chamber 21. This means for automatically throwing out the blower and compressor, and also for cutting off the feed of oil from the head tank 21, comprises a connecting device here shown as a cable 45 connected to the tank and passing through suitable guide sheaves 46, the lower end of the cable being provided with a rod or other suitable member 47, weighted at its lower end 48 and carrying stop collars 49 adjustably mounted and spaced on the rod 47. These collars 49 are adapted to move and throw a lever 50 which is mounted upon a pivot-shaft 51, the lever having angularly spaced lugs 52 adapted to engage a trip device or weight 53 loosely mounted on the spindle 51, the device 53 having lugs 54 engageable with adjacent portions of a walking beam or actuator 55, pivoted upon the shaft 51, one end of the actuator 55 being connected by a link 56 to a lever 57, pivoted at 58 upon a suitable support or portion of a frame supporting the head tank 21, the lever 57 being connected at its opposite end to a link 59, which in turn is joined to a throttle valve member 60 for controlling the motor 38, of whatever type it may be. The opposite end of the actuating lever 55 on the shaft 51 is connected to a link 61, the upper end of which is joined to the lever 28 which engages the collars 27 on the cut-out needle valve 23.

The operation of the automatic cut-out mechanism is as follows: When the gasometer rises toward its highest position the cable or connection 45 permits the rod portion 47 to descend, so that the upper collar 49 will engage the upwardly inclined lever 50 and gradually swing this downwardly; one of the stops 52 on the lever 50 will en-

gage the throw-over or weight 53, carrying it to a substantially vertical position, when it will freely gravitate around the pivot or shaft 51 and engage the opposite lug 52 on the lever 50, the gravitating motion of the weight 53 throwing the lever down and also engaging at one of its shoulders 54 the opposite side of the actuating lever 55, so that it will pull down the link 61, and this downward movement being transmitted through the lever 28 will press the needle valve 23 down to cut off the feed to the regulating valve 20, thus stopping the feed of oil to the carbureting chamber 15; as the valve 15 actuating link 61 moves down the link 56 will be drawn up and rock the lever 57, which in turn will through means of the link 59 throw the valve 60 to cut out the motor 38, thus stopping the operation of the blower 39 and the air compressor 37. As the mixture is exhausted from the buoyant gasometer 2, the latter will gravitate downwardly and through means of the connection 45 will lift the rod 47, so that the lower collar 49 thereon will be brought into operative engagement with the now downwardly inclined lever 50, this being moved upwardly meanwhile engaging and lifting the weight of the device 53 carrying it again into vertical position, from which it will automatically gravitate about the pivot 51 and swing into actuating contact with the adjacent or right-hand side of a lever 55 and throw this quickly so as to rock the lever 57 for opening the motor controller 60 and simultaneously lifting the needle valve 23 for the admission of oil from the feed chamber 21 past the regulator valve 20 to the carbureter. This constant opening, operative and inoperative relation of the parts provide for a continuous supply of the mixture in the gasometer 2.

The richness of the mixture can be varied by the quantity of oil passing through the regulator valve 20 from the feed chamber 21 to the carbureter chamber 15, and irrespective of the amount passing through the float valve, the float 30 will automatically operate the valve 33 to open or close the feed pipe 34, thus maintaining a substantially constant level and the desired quantity of oil in the feed chamber 21. By maintaining a free circulation of oil between the tank 13, and the feed tank 21 the excess will flow freely from the feed tank 21 through the overflow pipe 12 to the tank 13. In order to prevent any return of liquid in the feed pipe 34 or the air pipe 36, these are each provided with respective check valves 34' and 36'.

From the foregoing it will be seen that I have provided an air carbureting apparatus involving features designed to reduce the element of danger by explosion to a minimum, by providing a direct feed cham-

ber which will contain a relatively small quantity of oil. Secondly, the apparatus is designed to produce a mixture of substantially uniform richness by reason of the supply of oil from the chamber 21 of constant uniformity as to grade; and, thirdly, I have devised an apparatus which is simple in construction, automatically operable, and in which the chamber 15 is free from moving elements, thereby avoiding any chance of inoperation from clogging or other untoward causes.

Having thus described my invention what I claim and desire to secure by Letters Patent, is:

1. An apparatus for generating a combustible mixture from a liquid source, comprising a substantially vertical carbureter chamber, a perforated feed pipe mounted in the chamber, upwardly inclined deflectors in the chamber, means for forcing a column of air upwardly through the chamber, a feed chamber mounted upon the upper end of the carbureter chamber, a valve for regulating the volume of oil passing from said feed chamber to the feed pipe in the carbureter, and means for automatically maintaining a predetermined level of the liquid in said feed chamber. 80

2. An apparatus for generating a combustible mixture from a liquid source, comprising a substantially vertical carbureter chamber, a perforated feed pipe mounted in the chamber, upwardly inclined deflectors in the chamber, means for forcing a column of air upwardly through the chamber, a feed chamber mounted upon the upper end of the carbureter chamber, a valve for regulating the volume of oil passing from said feed chamber to the feed pipe in the carbureter, means for automatically maintaining a predetermined level of the liquid in said feed chamber, and a cowl mounted above the carbureter chamber having its lower edge in close juxtaposition to the level of the liquid in said feed chamber, whereby the heavier particles of moisture in the air column from the carbureter chamber will be thrown down before issuing from the feed chamber. 100

3. An apparatus for generating a combustible mixture from a liquid source, comprising a substantially vertical carbureter chamber, a perforated feed pipe mounted in the chamber, upwardly inclined deflectors in the chamber, means for forcing a column of air upwardly through the chamber, a feed chamber mounted upon the upper end of the carbureter chamber, a valve for regulating the volume of oil passing from said feed chamber to the feed pipe in the carbureter, means for automatically maintaining a predetermined level of the liquid in said feed chamber, a cowl mounted above the carbureter chamber having its lower edge in close juxtaposition to the level of the liquid 110

in said feed chamber, whereby the heavier particles of moisture in the air column from the carbureter chamber will be thrown down before issuing from the feed chamber, and an operating valve for controlling the flow of the liquid from the feed chamber to the regulator valve.

4. An apparatus for generating a combustible mixture from a liquid source, comprising a substantially vertical carbureter chamber, a perforated feed pipe mounted in the chamber, upwardly inclined deflectors in the chamber, means for forcing a column of air upwardly through the chamber, a feed chamber mounted upon the upper end of the carbureter chamber, a valve for regulating the volume of oil passing from said feed chamber to the feed pipe in the carbureter, means for automatically maintaining a predetermined level of the liquid in said feed chamber, a cowl mounted above the carbureter chamber having its lower edge in close juxtaposition to the level of the liquid in said feed chamber, whereby the heavier particles of moisture in the air column from the carbureter chamber will be thrown down before issuing from the feed chamber, an operating valve for controlling the flow of the liquid from the feed chamber to the regulator valve, and an automatically operating valve for maintaining a constant level of said fluid in the said chamber.
5. In combination, with a carbureter chamber, a feed pipe extending through the chamber, a series of baffles connected to the pipe, said pipe having a series of discharge openings, one for each baffle, means to feed oil to the upper end of the pipe and means to supply air to the lower end of the chamber.
- 40 6. In combination, with a carbureter chamber, a feed pipe extending through the chamber,

ber, a series of baffles connected to the pipe, said pipe having a series of discharge openings one for each baffle, a feed chamber inclosing the upper end of the carbureter chamber, a discharge pipe leading into the feed chamber, a cowl overlying the upper end of the carbureter chamber and surrounding the latter in spaced relation thereto to form a downwardly directed discharge for the carbureter chamber, means connected to the feed chamber and pipe to supply liquid to the latter, and means to feed air to the lower end of the carbureter chamber.

7. In combination with a carbureter chamber, a feed chamber into which the upper end of the carbureter chamber extends, a cowl surrounding the upper end of the carbureter chamber and projecting below the top end of the latter to form a downwardly directed discharge for the latter, a discharge for the carbureted air leading into the feed chamber, and means to feed liquid from the feed chamber to the carbureter chamber.

8. In combination with a feed chamber, a carbureter chamber having its upper end projected into the feed chamber so as to be submerged in the fluid in the feed chamber, a feed pipe leading from the feed chamber and discharging in the carbureter chamber, a discharge for the carbureted air leading from the feed chamber, and means to feed air to the lower end of the carbureter chamber.

In testimony whereof I have hereunto set my hand in the presence of two subscribing witnesses.

FRED S. OLIVER.
